7 Claims. (Cl. 18—24)

1

This invention has to do with the making of candles of the kind consisting of a wick surrounded by a low fusing combustible mass that may e. g. be paraffin or wax and will in the following be referred to as candle material.

Such candles are nowadays mostly produced by a mold casting process, since this is generally considered the cheapest way of making such candles. To some extent, however, the old immersion process, in which a wick is repeatedly immersed into a molten bath of candle material to form a deposit of desired thickness thereon, is still in use in various modified forms. However, the immersion process as hitherto conducted is generally more expensive than the mold casting process and is therefore normally only resorted to where it is desired to produce so-called "hand-made" candles, i. e. candles that are to have a particularly decorative or "antique" appearance.

The main reason for the higher costs of the immersion process is that it has not been found possible to conduct the process in such a manner as to allow for large scale production while at the same time maintaining the ideal conditions for the formation of the candles. The fact is that there are a great number of factors that are essential to the quality of candles produced by immersion. In the first place, when a good and uniform product is desired, care should be taken that all of the candles under production are uniformly cooled between each two successive immersions to a temperature that is neither too high nor too low, because if the temperature is too high, the layer deposited in the next immersion step will be too thin to warrant an economic production, while, on the other hand, if the temperature is too low, the layers deposited in successive immersion steps will not melt together satisfactorily so that small cavities, scale formation or the like irregularities may result. Secondly, the candles are very sensitive during the production to any influence resulting from currents of air and movement, even relatively insignificant currents of air sometimes resulting in warping of the candles.

If an attempt is made at producing candles by the immersion of large bundles of wicks, the difficulty is encountered that it is practically impossible to obtain a uniform cooling of the candle workpieces between the immersions. The fact is that the candles near the centre of the bundle will have a tendency to be cooled more slowly than the candles near the periphery of the bundle, and this tendency cannot very well be counteracted by ventilation, since this would result in

2

unfavourable currents of air as above explained, but even if this were feasible, the different conditions of heat radiation from the inner and outer candles respectively would result in similar differences in temperature, and seeing now that the inner candles must be cooled down sufficiently, it follows that the outer candles will be cooled down to a too low temperature so that the layer next deposited will not adhere properly. Besides, the finished candles will not be of uniform thickness, since in each immersion step a thicker layer will be deposited on the outer than on the inner candles.

One object of the invention is to devise a method and apparatus whereby candles of a good quality can be produced by immersion at competitive prices as compared with the mold casting process.

Another object of the invention is to make possible the large scale production of so-called "hand-made" or "antique" candles of high quality.

A further object of the invention is to provide a simple and reliable machine in which candles may be produced in large batches with a minimum of manual labor and without the necessity of transferring the candles to other machines for further treatment or subjecting the candles to any kind of individual treatment or post treatment.

With these and other objects in view which will appear from the following, the production of candles by immersion in large bundles is made possible with good and uniform results according to one feature of the invention by immersing said bundles into a cooling liquid between successive immersions into the bath of candle material, and since the candles will generally have a tendency to float on the cooling liquid, that may be water, and thereby to interfere with one another, it is further suggested according to the invention to subdivide the space in which the cooling liquid is active into a number of individual cells, one for each of the wicks in the bundle.

Other features and objects of the invention will be apparent from the following detailed description of some ways of carrying out the invention, reference being now had to the accompanying drawings in which:

Fig. 1 is a front view of one form of a machine constructed to carry out the principles of the invention.

Fig. 2 a top view of the machine with certain parts removed or broken away,

Fig. 3 an end view of the machine.

Fig. 4 on a larger scale a fragmentary vertical section through a cooling vessel forming part of the machine.

Fig. 5 a corresponding top view.

Fig. 6 a fragmentary vertical cross section through a wick holder or wick carrier with clamping means for the wicks.

Fig. 7 a fragmentary vertical longitudinal section through the same parts.

Fig. 8 a top view of a wick detaining device preparatory to being slid into its operative position.

Fig. 9 on a larger scale a vertical longitudinal section through the wick detaining device in its operative position, and

Fig. 10 a corresponding top view with parts in section.

In the drawings, 1 is a bottom frame from which four posts 2 project upwards to support a top frame 3 on which are mounted four bearings 4 for two shafts 5 and 6 carrying a number of sprockets 7 serving to guide four chains 8 carrying a block 9 at their ends depending between the posts 2 and having their respective other ends attached to a counterweight 10. The shaft 6 further carries a sprocket 11 which by a chain drive 12 is coupled to a sprocket 13 on a shaft 14 carrying a hand crank 15 and a pointer 16 rotatable in front of a calibrated disc 17. By turning the hand crank 16, the block 9 may be lifted and lowered, and the pointer 16 will indicate the level of the block 9, so that it is possible to control or check with relative great accuracy the level to which the block 9 is lowered.

The block 9 serves as a wick holder or wick carrier and consists of a frame 18 having a bottom 19 composed of a wooden sheet and a metallic sheet. Supported on the bottom 19 is a wick clamping device consisting of a system of mutually parallel outer tubes 20, in each of which an inner tube 21 is slidably mounted. Each outer tube has a series of vertical holes 22 extending therethrough, and each inner tube has a similar series of vertical holes 23. At one end of the frame, a bar 24 is arranged, and between the latter and each of the inner tubes 21 there is interposed a helical spring 25. The bar 24 may be urged towards the frame 19 by means of screws 26, and thereby each of the inner tubes is elastically displaced relative to its associated outer tube. In this manner, the holes of the inner tubes may be brought in line with the holes of the outer tubes, or alternatively in a displaced position relative to the latter. At their ends remote from the bar 24 each of the inner tubes may be influenced by a spring tending to move the inner tubes to the position in which the holes thereof are in line with those of the outer tubes, and this movement of the inner tubes may be effected against stop means serving to locate the inner tubes in the said position. These additional springs and stop means are, however, not absolutely necessary to obtain a satisfactory operation of the machine, since it has been found that the inner tubes have a tendency to move to the position in which their holes are in line with those of the outer tubes already under the influence of the wick threads to be passed through the holes of the inner and outer tubes.

Under the bottom 19, a guide tube 27 is mounted in line with each of the holes of the outer tubes. At their lower ends, the guide tubes are cut off in such a manner that a lip 28 is

formed projecting downwardly from the mouth of each guide tube.

When the machine is to be taken into use, a continuous wick thread is pulled through each pair of holes 22 and 23 and the guide tube 27 thereunder by means of a suitable tool. These wick threads may e. g. be taken off from individual feeding rollers in boxes 66, and are passed through individual holes of a guiding member 29 arranged between the posts 2. The wick threads are pulled through in a length corresponding to the desired length of the candles, and when this has been done, one batch of candles after another may be produced without a fresh threading operation until the full length of the wick threads on the feeding rollers has been consumed. In each operating cycle, the wick threads are locked in the desired position by clamping the bar 24 towards the frame 19 so as to cause a displacement of the inner tubes 21 relative to the outer tubes 20 whereby the wick threads are clamped in the holes of the latter and thereafter depend from the wick carrier ready for immersion.

A carriage 31 runs on a ball track 30 associated with the bottom frame and carries a paraffin immersion vessel 32 and a water-filled cooling vessel 33. Each of these vessels has a circumferential shape substantially corresponding to that of the wick carrier 9. The paraffin immersion vessel 32 is preferably heat insulated and provided at its bottom with an electric heating element 34 controlled by a thermostat so as to keep the paraffin in the vessel at a substantially constant temperature somewhat above the melting point. The paraffin may be supplied to the immersion vessel from a preferably electrically heated paraffin melting vessel, not shown.

In the cooling vessel, there is arranged a system of closely packed vertical tubes 37 forming individual cells to guide the respective candle work pieces during the immersion into the cooling vessel. The tubes 37 extend from a level slightly below the edge of the cooling vessel to a level at some distance above the bottom thereof and are supported on the latter by means of a downwardly extending lip 67. A rubber hose for the supply of fresh cooling water is connected to the cooling vessel at the bottom thereof. The cooling vessel is provided with an overflow 38 and is further provided at its bottom with an outlet valve 39, said overflow 38 and said outlet valve 39 both communicating with a drain pipe 40 opening above a drain trough 41.

The carriage 31 is adapted to be reciprocated by means of a crank 42 and a connection rod 43 driven through a worm gear 68 by means of an electric motor 45 or by hand. The eccentricity of the crank is so selected that each half revolution of the crank alternately brings the immersion vessel 32 and the cooling vessel 33 in position vertically below the wick carrier 9. Well known means may be provided for automatically locking the crank in these extreme positions and for releasing it preparatory to starting its next movement.

The operation of the parts so far described is as follows:

When the wicks have been pulled through the wick carrier 9 in the desired length, as will be further described below, the wick carrier is lowered by turning the hand crank 15 so as to immerse the wicks into the immersion vessel which prior to this operation has been brought into position between the posts 2. The immersion may preferably be performed to a depth such that

paraffin is deposited on the wicks up to the middle of the lips 28 so that the wicks are caused to adhere to the lips which has a stabilizing effect against lateral swinging of the candle workpieces that have been formed by the described immersion and are now to be increased in thickness by subsequent immersions so as to finally develop into the finished candles.

The described operation may be repeated some times while the deposit on the wicks is still relatively thin, but when the deposit has assumed a certain thickness, it becomes essential for the reasons stated above that a positive cooling is performed between successive immersions, and this is done as follows:

When after an immersion of the candle workpieces into the immersion vessel, the wick carrier 9 has been lifted by turning the hand crank 15 so that the vessels may pass freely under the candle workpieces, the carriage 31 is moved by means of the crank 42 and the connection rod 43 to a position in which the cooling vessel is situated vertically below the wick carrier. The latter is now again lowered by turning the hand crank 14 so as to immerse the candle workpieces into the cooling vessel, whereby the candle workpieces are uniformly cooled. The individual cells formed by the vertical tubes 37 prevent the candle workpieces from interfering with one another and from escaping laterally owing to their light weight relative to the water in the cooling vessel. When the candle workpieces have been cooled, the wick carrier is again lifted, and the carriage 31 is moved so as to bring the immersion vessel into active position below the wick carrier whereupon the latter is again lowered to immerse the candle workpieces into the paraffin so that a further layer of paraffin will be deposited on the candle workpieces. The described cycle is repeated a number of times, until the candles have assumed the desired circumferential shape.

It has been found that by the operations above described the candles will over the greater part of their length assume a slightly tapering shape similar to that of the so-called "antique" candles. Moreover, by suitably conducting the immersion process, the candles may automatically be provided with a more brusquely tapering and somewhat rounded tip at their upper ends. This is done simply by immersing the candle workpieces to successively increasing depths in a succession of immersing operations. For instance, after one or a few preliminary layers have been deposited on the wicks, the latter may be immersed to such a depth that the paraffin extends only to some two centimeters from the point at which the final tip of the candle is to be formed. Then, in the next immersion, the candle workpieces may be lowered 1 to 2 millimetres further and so forth, whereby the desired rounded tip is formed in the course of say 18 to 20 immersions into the paraffin vessel with cooling steps in between.

At their bottom ends, the candles will assume a rounded shape which is usually not desirable. Accordingly, it is proposed, according to the invention, to flatten the lower ends of the candles simply by melting material therefrom. This may be done by lowering the candles against a tray 69, that normally rests on rails 57 outside the active space between the posts 2 and may be slid in between the latter after the wick carrier and the candles depending therefrom have been raised. The tray 69 may simply be provided with an elec-

tric heating element at its bottom, but preferably it contains a shallow bath of candle material kept at a temperature substantially above the melting point by means of an electric heating element. Such a bath has no tendency to deflect the depending candles from their vertical position, and it has been found that provided the temperature of the bath is high enough so that the melting of the immersed rounded ends of the candles proceeds with sufficient speed, the ends of the candles will assume a shape substantially as if cut off by means of a knife at the surface level of the melting bath.

During the immersion process, it is advantageous to effect a regulation of the liquid level in the cooling vessel as the immersion process proceeds and the candles assume a constantly larger volume so as to displace a constantly greater quantity of water. True, the cooling vessel is provided with an overflow, but if the excessive water is permitted to overflow this way, it is found that the overflowing water comes substantially only from the outer tubes 37, while there will practically not be any shift of water in the inner tubes 37 so that a temperature difference will come up between the cooling water in the inner and outer tubes which again results in a non-uniform cooling of the candles. It is therefore advantageous to extract water through the valve 39 gradually as the volume of the candles increases, and this of course need not be done continuously, but e. g. one or a few times in the course of the whole cycle of operations. The overflow then only serves as a security against flooding over the outer edge of the cooling vessel. It has been found preferable to shift the whole of the cooling water in the cooling vessel before the last cooling operation of a cycle and after the lower ends of the candles have been flattened as described so that a profound cooling of the finished candles is performed before they leave the machine, and the cooling water may then be left over for the next cycle of operations. Alternatively, the shift of cooling water may be effected between successive cycles.

In each cycle, the temperature of the cooling water in the cooling vessel will gradually increase, but this has been found to be rather an advantage than a disadvantage since the last layers are deposited more perfectly if the preceding cooling is not too profound.

As examples of the candle material wax and paraffin have been mentioned in the foregoing. These materials have been specifically referred to because they are particularly suitable for use in the process according to the invention on account of their plastic consistency when solidified. This is of importance because when immersing a wick into a melting bath, the material will not always be uniformly deposited on the wick, for which reason the wick may assume a slightly curved or warped configuration upon solidification of the material. When however, the solidified material is plastic, the wick with the solidified material thereon when depending freely will have a tendency to be straightened out by its own weight so as to assume the desired rectilinear form. If, on the other hand, a material is used, which solidifies in a stiff consistency, the candle workpiece will not be straightened in the manner described, and the final candles may therefore assume an irregular shape. Stearin as such is therefore not less suitable for the production of candles by the method here considered.

On the other hand, when using such plastic

materials as wax and paraffin, care should of course be taken to use these materials in a consistency such that the finished candles will not be too soft since otherwise they may assume a curved or warped appearance if subjected to a relatively high temperature during storage or in the place where they are used. In this respect stearin is superior since it remains entirely stiff until it is molten.

Now, in order to combine the advantages of a relatively plastic and a relative stiff material in such cases where difficulties might be encountered in finding a suitable compromise between the desired plasticity during production and the desired stiffness of the finished candles, it is proposed, according to one feature of the invention, to use a melting bath of a relatively soft mass such as paraffin in a first succession of immersion steps and a melting bath of a relatively stiff mass such as stearin in a subsequent succession of immersion steps.

In this connection it is to be remembered that plasticity is only required during the first immersion steps. Once a few layers have been deposited and the candle workpieces thus formed have been allowed to be straightened out under the influence of their own gravity, it is entirely possible without any danger of warping to make the subsequent layers of a stiffer material so that the final product thanks to the outer stiff layers remains perfectly in shape until molten. A similar effect could of course not be obtained just by mixing the two materials in the melting bath, though such mixing may of course be resorted to for the purpose of controlling the plasticity.

It is observed that the immersion cycle may also include one or more immersions into well-known chemicals to produce a "fancy" surface. This may be done without removing the candles from the machine simply by sliding a vessel containing the chemical in under the wick carrier and then lowering the latter.

When a batch of candles has been finished as described, the candles are to be removed from the wick carrier, and a new length of wick is to be pulled out through the holes of the tubes 20 and 21 of the wick clamping device and through each of the guide tubes 27. The arrangements serving this purpose will now be described.

At some distance from the posts 2, a frame 47 open at one end is pivotably supported between two posts 46 and is adapted to be swung from a vertical position to a horizontal position, in which the open end thereof registers and engages with the open end of a corresponding stationary frame 48 carried between the posts 2 and surrounding the working zone of the machine. The frame 47 carries a wick detaining device consisting of a system of mutually parallel outer tubes 49 each having an inner tube 50 slidably mounted therein. Each outer tube is provided along one side thereof with a number of notches 51 and each inner tube is provided along each corresponding side with a corresponding series of notches 52. The outer tubes 49 are fixed to a bar 53, and at a small distance from the latter, there is arranged another bar 54 that may be urged towards the bar 53, a helical spring 55 being interposed between the bar 54 and each of the inner tubes 50. By urging the bar 54 towards the bar 53, the inner tubes can be displaced from a position in which their notches are in line with those of the outer tubes to another position in which they are offset relative to the latter. Preferably, the inner tubes and the outer tubes may be provided

similarly as described with reference to the tubes 20 and 21, with spring and stop means 63 and 64 respectively for normally keeping the tubes 49 and 50 in a position relative to one another such that their notches are in line with one another.

When the frame 47 has been swung to the horizontal position, in which it registers with the frame 48, the whole of the wick detaining device may be slid as a unit from the frame 47 into the frame 48. During this sliding movement the individual pairs of tubes 49 and 50 are moved longitudinally in between the rows of candles depending from the wick carrier 9, and the latter will previously to this operation have been set in a vertical position such that the pair of tubes of the wick detaining device are level with the free wick end at the tips of the candles. Preferably, there is provided at the end of the frame 48 remote from the frame 47 a slideable bar 65 having holes for the engagement of the pairs of tubes 49 and 50, so that the latter are hereby supported and caused to assume a predetermined position relative to the candles depending from the wick carrier, viz. a position such that each wick is situated immediately outside one of the notches of the pairs of tubes, the notches of the outer and inner tubes being flush at this stage.

Now the wick detaining device is laterally displaced as a unit whereby a wick enters into each of the notches 51. Thereafter the bar 54 is urged towards the bar 53, so that the inner tubes are displaced relative to the outer tubes and cause the wicks to be gripped and clamped in the notches in the pairs of tubes.

The candles are now ready to be cut off from the continuous wick threads, but prior to this, a new length of wick is to be pulled out. Also, suitable must of course be provided for collecting the candles when cut off. Such means may consist of a carriage or slide 56 adapted to be run in under the wick carrier on the guide rails 57 and carrying a tray 58 with two perforated trays or sheets 59 and 60 forming cells for receiving the individual candles. If such a carriage and associated tray is used, it should of course be run into position before the wick carrier is lowered to the position in which the wick detaining device is to be set in operation, or in other words, the candles will already be seated in the cells of the tray 58, when the wick detaining device is brought into action as above indicated.

When the wicks have been clamped in the wick detaining device, the bar 24 is released so that the inner tubes 21 are permitted to move to a position in which their holes are in line with those of the outer tubes 20. Thereafter, the wick carrier 9 is moved upwards, whereby a new length of wick is pulled out through the wick clamping device and the tubes 27. When the desired length of wick has been pulled out, the bar 24 is tightened again, so that the wick threads are clamped in the wick clamping device in the new position.

Thereafter the candles already produced are cut off by passing a knife 76 slidably mounted under the wick carrier through the whole bundle of wicks clamped in the wick detaining device. Now, the finished candles may be rolled away on the carriage 56 to be packed, and after the wicks have been released from the wick detaining device by releasing the bar 54, the wick detaining device may again as a unit be slid into the frame 47 whereupon the latter may be swung to its vertical position. The machine is then ready for

the commencement of a fresh operation cycle to produce another batch of candles.

I claim:

1. A machine for the making of candles comprising a wick holder having means for the attachment of a large number of continuous wick threads in positions to depend freely from said wick holder in mutually spaced relationship and in a length substantially corresponding to the desired length of a candle, an upwardly open vessel 10 for receiving a bath of candle material, and upwardly open vessel for receiving a cooling liquid, means for horizontally displacing said vessels and said holder relative to one another to bring said holder in position above one or the other of said vessels, means for vertically moving said holder up and down relative to said vessels to immerse and withdraw said wicks into and from the respective liquids therein, a horizontally disposed rectangular first frame open at one end and surrounding the working zone of the machine as defined by the ascending and descending movement of said wick holder, a second frame likewise open at one end and mounted for rotation about a horizontal axis between a substantially vertical position and a substantially horizontal position in which the open end thereof registers with the open end of said first frame, a wick anchoring device including a plurality of mutually parallel elongated wick engaging members constructed to engage a row of wicks from one side and having means associated therewith for clamping the wicks thus engaged, said wick anchoring device being normally seated in said second frame and being longitudinally slidable therefrom, in the substantially horizontal position thereof, into said first frame to bring said wick engaging members in position between rows of wicks depending from said wick holder and being thereupon transversely slidable to engage such rows of wicks from the side whereby when the wicks have been thus engaged and then clamped, the wick holder upon loosening of the wick threads relative thereto may be moved upwards to pull out fresh lengths of wick thread.

2. A machine as in claim 1, in which a transversely slidable supporting bar is provided at the closed end of said first frame and having holes for receiving and supporting the ends of said wick engaging members.

3. A process for the production of candles comprising the steps of immersing a bundle of candle workpieces freely depending in mutually spaced relationship from a common holder alternately into a bath of low melting combustible material and into individual cells of a liquid cooler a sufficient number of times to form on said candle workpieces a deposit of combustible material of desired thickness to form the finished candles, and then immersing the ends of said finished candles into a shallow bath at a temperature substantially above the melting point of the candle material so as to flatten said ends by a melting operation.

4. A machine for making candles comprising a wick holder having means for the attachment of a large number of continuous wick threads in positions to depend freely from said wick holder in mutually spaced relationship and in a length substantially corresponding to the desired length of a candle, a first upwardly open vessel for receiving a batch of candle material, a second upwardly open vessel for receiving a cooling liquid, a plurality of closely packed vertical tubes open at both ends provided in said

second vessel in a position to horizontally subdivide the active area of said second vessel into a number of individual cells in a pattern corresponding to that of said depending wicks, means for horizontally displacing said vessels and said holder relative to one another to bring said holder in position above one or the other of said vessels, and means for vertically moving said holder and said vessels relatively to one another to immerse said wicks into said vessels.

5. A machine for making candles comprising a wick holder having means for the attachment of a large number of continuous wick threads in positions to depend freely from said wick holder in mutually spaced relationship and in a length substantially corresponding to the desired length of a candle, a first upwardly open vessel for receiving a batch of a candle material, a second upwardly open vessel for receiving a cooling liquid, means in said second vessel for horizontally subdividing the active area thereof into a number of individual cells being open at both ends and extending over part of the depth only of said second vessel, said individual cells forming a pattern corresponding to that of said depending wicks, means for horizontally displacing said vessels and said holder relative to one another to bring said holder in position above one or the other of said vessels, means for vertically moving said holder and said vessels relatively to one another to immerse said wicks into said vessels, and means for extracting cooling liquid from said second vessel at a level below said individual cells.

6. A machine for making candles comprising a wick holder for the attachment of a large number of continuous wick threads in positions to depend freely from said wick holder in mutually spaced relationship and in a length substantially corresponding to the desired length of a candle, a guide tube for each wick thread mounted on the underside of said wick holder, a wick stabilizing member depending from the mouth of each of said guide tubes in a position such that the respective wick thread may adhere thereto after the first immersion, a first upwardly open vessel for receiving a batch of candle material, a second upwardly open vessel for receiving a cooling liquid, means in said second vessel for horizontally subdividing the active area thereof into a number of individual cells in a pattern corresponding to that of said depending wicks, means for horizontally displacing said vessels and said holder relative to one another to bring said holder in position above one or the other of said vessels, and means for vertically moving said holder and said vessels relatively to one another to immerse said wicks into said vessels.

7. A machine for making candles comprising a wick holder for the attachment of a large number of continuous wick threads in positions to depend freely from said wick holder in mutually spaced relationship and in a length substantially corresponding to the desired length of a candle, a guide tube for each wick thread mounted on the underside of said wick holder, a wick stabilizing member depending from the mouth of each of said guide tubes in a position such that the respective wick threads may adhere thereto after the first immersion, a plurality of wick engaging members forming part of said wick holder and each comprising an outer tube having a series of lateral notches, and an inner tube slidably mounted in said outer tube and

having a similar series of lateral notches, means being provided for simultaneously displacing all of said inner tubes relative to their respective outer tubes to selectively bring the notches of said inner tubes in line with the notches of said outer tubes to permit entrance of the wick threads into such aligned notches, or into a displaced position to clamp the wicks thus entered, a first upwardly open vessel for receiving a batch of candle material, a second upwardly open vessel for receiving a cooling liquid, means in said second vessel for horizontally subdividing the active area thereof into a number of individual cells in a pattern corresponding to that of said depending wicks, means for horizontally displacing said vessels and said holder relative to one another to bring said holder in position above one or the other of said vessels, and means for ver-

5

10

15

tically moving said holder and said vessels relatively to one another to immerse said wicks into said vessels.
